CLAIM

The ornamental design for an drive unit for electric assisted bicycle, as shown.

DESCRIPTION

FIG. 1 is a perspective view of an drive unit for electric assisted bicycle showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
